UNITED STATES PATENT OFFICE.

HORACE K. JONES, OF HARTFORD, CONNECTICUT, ASSIGNOR TO THE RUSSELL AND ERWIN MANUFACTURING COMPANY, OF NEW BRITAIN, CONNECTICUT.

MACHINE FOR ROLLING CARPENTERS' SQUARES.

SPECIFICATION forming part of Letters Patent No. 748,870, dated January 5, 1904.

Application filed January 23, 1903. Serial No. 140,362. (No model.)

To all whom it may concern:

Be it known that I, HORACE K. JONES, a citizen of the United States, residing at Hartford, in the county of Hartford and State of Connecticut, have invented certain new and useful Improvements in Machines for Rolling Carpenters' Squares, of which the following is a specification.

My invention relates to improvements in machines for rolling carpenters' squares; and the main object of my improvement is to produce a machine for rolling right-angular blades, like carpenters' squares, to a tapering thickness.

In the accompanying drawings, Figure 1 is a front elevation of my machine with parts broken out and in section. Fig. 2 is a side elevation of the left-hand side of the same with a part of the left-hand upright of the frame broken off. Fig. 3 is a plan view of my machine. Fig. 4 is a rear elevation thereof. Fig. 5 is a diagram, on a greatly-reduced scale, illustrating the manner of cutting the blades from a sheet of metal preparatory to rolling. Fig. 6 is an enlarged side elevation of the lifting-cam for the lever-pressure mechanism. Fig. 7 is a side elevation, partly in vertical section, of the boxes for the upper roll of my machine, the said figure being on a reduced scale as compared with Fig. 6, but enlarged from Figs. 1 and 2, which partially show the said boxes. Fig. 8 is an enlarged central longitudinal section, partly in elevation, of the clutch mechanism. Fig. 9 is a transverse section of the same on the line $x-x$ of Fig. 8, the gear-wheel that the clutch drives being omitted.

A designates the bed of the machine, having mounted thereon at one end the frame B for the rolls and adjacent parts and at the other end the frame C for mounting the driving-shaft D and connected parts. This driving-shaft is shown with its outer end broken off. These frames and their boxes or bearings for the respective shafts may as to their general construction be of any ordinary form. The frame B has two uprights 13 and 14, within which the rolls 6 and 7 are adjustably mounted to move to and from each other and to be held in their adjusted position for giv-

ing the necessary pressure. It is immaterial except for convenience of construction which one of the rolls is the movable or adjustable one; but, as shown, the lower roll 6 is fixed as to its position, and the upper roll 7 is the one that rises and falls to make the necessary adjustment. These rolls are on short shafts 8, one end of which is squared, as at 9, Fig. 1, or otherwise arranged for being engaged with and driven by the couplings 10 on the driving-shaft D and counter-shaft 11, having similar squared driving portions 9^a, whereby when the couplings are engaged the rolls move in unison with the shafts D and 11, while at the same time absolute alignment is not required. The squared portions 9^a are long enough to permit the couplings 10 to slip endwise for disengaging. The upper half-box 12 for the upper roll is made long enough for both ends of the said roll and extends from upright to upright of the frame B, as best shown in Fig. 1, in which the upright 13 is broken out and partially shown in section to show one end of the said half-box. Underneath the said half-box 12 and under the ends of the shafts 8 a lower half-box 12^a is secured in any proper manner—as, for example, by screws 35, Fig. 7—so that the upper roll necessarily rises and falls with the said half-box 12. At the top of this half-box 12 is a toggle-link 15, and on this link is the toggle-lever head 16, surmounted by another toggle-link 15 and cross-bar or abutment 17, all of which extend from upright to upright, as indicated by broken lines in Fig. 1. Setscrews 18 extend through the uprights 13 and 14 and rest on the cross-bar 17 for adjusting the position of the upper roll when it is forced downwardly by the toggle lever and links. A spring 19, the upper end of which is attached to cross-rod 20 and the lower end of which is secured to the upper half-box 12, has a constant tendency to lift the said half-box and upper roll to its uppermost position and does lift it or hold it up when the said half-box is not forced downwardly by the toggle lever, links, &c. This construction allows the spring 19 to lift the upper roll when the lever 21 is at its lowest position, thus leaving an open space between 100

the rolls for the insertion of the blank to be rolled. The toggle-lever 21 extends from its head 16 rearwardly to the cam 22, that is mounted on the cam-shaft 23 at the rear part of the frames B and C. This cam-shaft is driven by the gear-wheel 24 and clutch 25, the said wheel being loosely mounted on the said shaft while the clutch is rigid thereon, so that the shaft is driven by the said wheel 5 when the clutch is engaged therewith, but remains stationary while the wheel rotates when the clutch is disengaged therefrom. The clutch is of the ordinary spring-pin type, the pin snapping into engagement with the wheel 24 whenever the said pin is released and staying in engagement until it is withdrawn. This clutch 25 is shown in detail in Figs. 8 and 9. The gear-wheel 24, a part only of which is shown in Fig. 8, has two or more 10 pin holes or pockets 43, concentrically arranged on the side that faces the clutch. A sliding pin 44, having a shoulder 45, is mounted in the clutch-body and provided with a spring 46, one end of which spring bears on the bottom of the hole within the pin in which the said spring is seated, while the other end of the spring abuts against the cap 47, whereby the said spring exerts a constant tendency to force the pin 44 toward the gear-wheel 24. 15 The clutch-lever 27 has a beveled or wedge-shaped end 28 and a holding-face 48. A spring 49, with one end secured to said lever and its other end hooked to the frame or any fixed support, has a tendency to hold the end 20 of the clutch-lever up against the under side of the chuck in the position shown in Fig. 9. The clutch-pin is of a length to strike bottom in the hole or socket in the gear-wheel when the shoulder 45 is a little distance from the 25 confronting side face of the annular groove in the clutch, so as to leave a free space for the point of the clutch-lever to enter. When the clutch-lever is depressed to remove the beveled end 28 from the path of the shoulder 30 of the clutch-pin, the said pin under the influence of its spring enters the first hole or socket in the gear-wheel that presents itself to said pin. The gear-wheel and clutch will then rotate together so long as the clutch-lever is depressed. As soon as the clutch-lever is released to have the spring 49 draw the beveled end up to the clutch said end engages the shoulder 45 at the first revolution of the clutch and withdraws the pin, 35 which is stopped with its shoulder resting on the holding-face 48. If the clutch-lever is released immediately after its withdrawal, the clutch will stop the gear-wheel 24 and parts driven thereby at the end of the first 40 revolution of the clutch.

The bed A may rest upon any table, bench, or support, the top of which is indicated by the base-line E, Figs. 1 and 4, and on the said support is a clutch-lever bracket 26. The 45 clutch-lever 27 is mounted on the said bracket with its usual curved and beveled end 28, adapted to enter the ordinary groove in the

clutch to withdraw the clutch-pin as the said pin rides up the incline or bevel of the clutch-lever, as in ordinary clutches of this class. 70 The clutch-lever 27 is thrown out of engagement with the clutch by means of the foot-treadle 29 and bar 30, connecting the end of the foot-treadle with the said lever. Any suitable spring may be employed for forcing 75 the clutch-lever and treadle into the position for making the said lever engage the groove of the clutch. The gear-wheel 24 engages with and is driven by a similar gear-wheel 31, fixed on the driving-shaft D. The said 80 driving-shaft is connected with the counter-shaft 11 by means of the pinions 32. It will thus be seen that the treadle and clutch devices constitute mechanism for starting and stopping the cam while the rolls rotate. 85

In Fig. 5 I have shown how the square blanks or blades may be cut from a plate of metal of the proper thickness. These blanks, it will be seen, are right-angular blades that cannot be passed endwise through the rolls between ordinary uprights. I have therefore made the upright 13 of a special construction designed expressly for the introduction of substantially the whole length of either square blade into the rolls for being 90 operated upon. This I accomplish by forming a blade-space 33 in the front of the upright 13, which space extends back to or a little beyond the central point of the rolls, as shown in Figs. 1 and 2. In order to give the 95 said upright the proper strength, I form a web 34 across the ends of the boxes and on the outer side of the upright near its upper end. This blade-space is designed to receive one blade into it, while the other blade is 100 passed directly endwise between the rolls far enough to permit the rolls to act on the said blade from the angle to the outer end thereof. As shown, the cam-shaft and driving-shafts are geared so as to revolve at the same 105 speed when both are moving; but the gearing can be varied, according to the work required. The size of the rolls, as shown, is such as to traverse one of the longer blades at one revolution of the cam-shaft and rolls— 110 that is to say, roll a blade that is two feet long at one revolution. The clutch and the cam are so mounted on the shaft that the clutch-pin is withdrawn and stops the cam-shaft just as the highest point of the cam 115 passes the end of the toggle-lever, which then falls to open the rolls. The shape of the cam is clearly shown in Fig. 6. This cam is of the proper shape and size for operating the lever mechanism of the rolls to give the desired taper at one revolution of the cam to the longer square blade, (which is two feet long.) The cam has a short seat 36 just in the rear of the drop 37 back of its highest point 38. From this seat the cam-face rises 120 very rapidly for the first quarter of a revolution from the said drop, making nearly but not quite one-half of all its rise on the said first quarter, over half of this being made at

the first eighth of a revolution. The radial broken lines 39, 40, 41, and 42 indicate, respectively, the first eighth, quarter, half, and three-quarters of a revolution from the drop 5 37, while the broken circle around the cam indicates the path of the highest point 38 of the cam, thereby more clearly showing the rise or eccentricity. About two-thirds of the entire rise of the cam is made during its first half of a 10 revolution, while only about one-eighth of the entire rise is made on the third quarter and, as shown, only about one thirty-third on the last quarter. The most essential part of the 15 cam is its first half, while the rise on the fourth quarter is so slight that the cam may be said to be practically concentric at that quarter. It might be, in fact, concentric without materially changing the general operation of the machine. This cam may be used, if desired, 20 when rolling the shorter square blades. When the end of the lever 21 rests upon the short seat 36, the rolls, if properly adjusted, will be opened a little in excess of the thickness of the blank square blades to be rolled, so 25 that the said blades can readily be passed between the blades when the rolls are moving.

An ordinary square blade is so thin that when it tapers in thickness from end to end the taper must necessarily be very slight. In 30 this connection it should be noted that the rise in the cam, as herein shown, is many times more than the rise and fall of the upper roll, the lever and toggle-links acting as mechanism for reducing motion, whereby the 35 motion of the cam imparts a comparatively slight closing motion to the rolls. By the employment of mechanism for reducing motion between the cam and the rolls I am enabled to close the rolls gradually and evenly with 40 a powerful pressure. The operator pushes a blade endwise between the rolls until the connecting portion of the two blades comes between the rolls, while the member or blade not to be then rolled projects to the left 45 through the blade-space 33. He then puts his foot on the treadle 29 to withdraw the clutch-lever 27 and permits the spring-pin of the clutch to engage the wheel 24 to start the cam-shaft. The cam then acts on the mechanism 50 comprising the toggle lever and links to force the rolls together, and as soon as the rolls pinch the blade it moves outwardly toward the front, the rolls coming closer and closer together as the blade moves along, so 55 as to roll the blade to a tapering thickness. The machine may readily be adjusted so that the rolls will begin to act on the blade being rolled at a point substantially in alignment with the inner edge of the companion blade. 60 Inasmuch as the object of having the square the thickest at or near the angle is to strengthen the angle, the taper may decrease faster for the first few inches from the angle than for the rest of the blade. In fact, the 65 thinnest end of the longer blade may, if desired, be of a uniform or nearly-uniform thickness for some length. As soon as the

cam-shaft is started and the rolls begin to act on the blade the operator releases the foot-treadle and clutch-lever, so that the spring-pin of the clutch is caught and the cam is stopped after making one revolution, during which the blade will be ejected from the rolls and the machine is ready to receive another blade. The machine may be arranged for rolling one of the longer blades to the desired taper at one revolution of the cam, and the shorter blade may be rolled under the same conditions, and it will correspond in taper and thickness to the longer blade for a distance from its 75 companion blade corresponding to its length. If the machine is made to taper the whole length of the longer blade and both blades are then rolled, the result is that the shorter blade is not quite so thin at its thinnest end. 80 If desired, all the long blades may be rolled with the machine adjusted or arranged in one way and the shorter blades rolled afterward under a different adjustment or with a different cam. If the stock or amount of taper is such that it cannot be rolled by once 85 passing the blade between the rolls, the blade may be inserted for only a part of its length between the rolls and then starting the machine to force the rolls together and have them 90 first pinch or act on the blades at the middle of their length or at any desired point removed from the connected ends of the blades. At the next operation the blade may be inserted a little farther or at its whole length. 95 In this manner the blades can be rolled at only one or several passes by merely inserting a greater or less portion of their length between the rolls for the rolls to act upon at 100 each pass.

It is apparent that some changes from the specific construction herein disclosed may be made, and therefore I do not wish to be understood as limiting myself to the precise form of construction shown and described, but desire the liberty to make such changes in working my invention as may fairly come within the spirit and scope of the same.

I claim as my invention—

1. In a machine for rolling squares, the 115 combination of the rolls with the frame comprising two uprights in which the said rolls are mounted, one of the said uprights of the said frame having the blade-space, open at the front and extending back to the central 120 point of the rolls.

2. The combination of the frame with the rolls mounted in the front part thereof, one of which rolls is movable to and from the other, a cam-shaft mounted at the rear part of the 125 said frame, gearing connecting the said cam-shaft and rolls, a cam on the said cam-shaft, toggle-links arranged in the plane within which the axis of both of the said rolls lie, and an operating-lever extending from the said 130 links to the said cam.

3. The combination of a frame with the rolls mounted therein, one of the said rolls being movable to and from the other, a cam mount-

ed in the frame separately from the said rolls, the toggle-links and the lever having a head at one end lying between the said links and by which the said lever is fulcrumed, the other end of the said lever being acted upon by the said cam.

4. The combination of the frame having uprights, with the rolls and roll-boxes, one of the rolls and its boxes being mounted to rise and fall within the said upright, a toggle-link with one end mounted on the said boxes, a lever-head mounted on the other end of the said toggle-link, a cross-bar or abutment, a second toggle-link with one end mounted on the said abutment and its other end on the said lever-head, a lever extending laterally to the axis of the rolls from the said lever-head and rigid with the said head, and a cam for acting on that end of the said lever which is opposite the said head.

5. The combination of the rolls, one of which is movable to and from the other, with a cam rotating in connection with the said rolls, and mechanism between the said cam and rolls for reducing the motion of the said cam, substantially as described.

6. The combination of the rolls, one of which is movable to and from the other, with a cam having the drop and rising face extending from bottom to top of the said drop, the said face making the major part of its lift at the first three-quarters of its revolu-

tion from the said drop and its most rapid lift within its first quarter of a revolution from the said drop, and mechanism between the said cam and rolls for reducing the motion of the said cam.

7. The combination of the rolls, with the toggle-links and lever acting as mechanism for reducing motion, and the cam having the drop and rising face for acting upon the said lever, the most rapid lift of the said cam-face being at the first quarter of its revolution from the said drop.

8. The combination of the rolls, one of which is movable to and from the other, with a cam and connecting mechanism for acting upon the said movable roll for forcing the rolls together, and mechanism for starting and driving the said cam and for stopping it at a predetermined point of its movement.

9. The combination of the rolls, one of which is movable to and from the other with a cam which may rotate in connection with the said rolls, mechanism between the said cam and rolls for reducing the motion of the said cam, and mechanism for starting the cam and then stopping it at the end of one or more complete revolutions.
